UNITED STATES PATENT OFFICE.

WILLIAM G. ROSS, OF CHICAGO, ILLINOIS.

TURBINE.

990,781.

Specification of Letters Patent. Patented Apr. 25, 1911.

Application filed April 9, 1910. Serial No. 554,487.

To all whom it may concern:

Be it known that I, WILLIAM G. Ross, a citizen of the United States of America, and a resident of Chicago, county of Cook, State of Illinois, have invented certain new and useful Improvements in Turbines, of which the following is a specification.

The main objects of the present invention are to provide an improved type of rotary engine constructed to utilize in an efficient manner, the expansive or impulsive energy of a fluid; to provide a rotary engine having a rotor of special construction, and with tubular buckets passing therethrough from one side to the other; to provide a casing for this rotor and having chambers which serve as conduits to conduct the driving fluid to a plurality of buckets in succession; to provide improved heating means for steam driven turbines whereby the steam, while being conducted from one bucket to another can be heated, thereby reducing condensation in the passages; and to provide other improvements in the construction whereby the engine will be efficient and reliable in operation, inexpensive to maintain and of low initial cost.

A specific construction embodying this invention is shown in the accompanying drawings, in which:

Figure 1 is a side elevation with part of the steam jacket broken away to show an end plate of the casing with the steam chests mounted thereon. A portion of that end plate is broken away to show the rotor. Fig. 2 is a sectional elevation, the section being taken along the line A—A of Fig. 1, but following an irregular course in such a way that the two tubular portions of each bucket appear in the figure as being in direct alinement, although in the actual structure they meet at an obtuse angle. Fig. 3 is a sectional development of a part of the rotor and its casing, and shows the relation of the steam chests whereby steam projected from a nozzle into one bucket can be conducted around to another bucket, and so on in succession through a series of buckets, the section corresponding to the surface of a cylinder, as for instance, that represented by the line B—B of Fig. 1. Fig. 4 is a detail of the inlet nozzle. Fig. 5 is a section of the same on the line C—C of Fig. 4. Fig. 6 shows a modification wherein the steam which is delivered through a bucket near the periphery of the rotor is conducted through

a steam chest to a bucket located nearer the shaft, and so on in succession until it finally leaves the rotor from one of the buckets nearest the axis. Fig. 7 is a partial irregular section, having the general direction of the line D—D of Fig. 6, the section being taken in such a way that the two converging halves of each bucket appear in the figure as a straight tube. Fig. 8 is a diagrammatic representation of the means for conducting away water of condensation from the steam chests in turbines of large sizes.

In the construction illustrated in Figs. 1 to 5, inclusive, the rotary engine comprises a shaft 1, carrying a rotor. This shaft is journaled in end plates 2 and 3, which constitute the side walls of the casing within which the rotor turns. The plates are securely fastened to a base 4, as by means of bolts 5, and can be moved toward each other a short distance by means of an adjusting screw 6. An annular band 7 may be secured to the outer edges of the plates to form the outer wall of the casing or chamber, within which the rotor turns. Bolted to the outer face of each end plate is an annular steam jacket 8, through which superheated steam may be circulated to maintain a high temperature. Within each steam jacket and bolted to the outer face of the end plate are a plurality of casings or steam chests 9, each having an inlet port and an outlet port, and each serving as a conduit through which steam delivered or released from one bucket can be expanded and heated and then conducted forward to another bucket. The chests 9 are preferably larger in transverse section than the nozzle area of the passages through the buckets so as to reduce the frictional resistance to the flow of steam through the chests and provide pockets for collecting condensation in the larger sizes of engines. In such larger sizes of engines, each of the steam chests may have a trapped outlet pipe connected to its lower part for conducting away the water resulting from condensation of the steam. In order to avoid confusion of the drawings, these pipes are shown only in Fig. 8, and are there shown diagrammatically.

The rotor comprises a pair of disks 10 and 11, each having a hub keyed to shaft 1. Mounted on the inner or adjacent faces of these hubs are a pair of annular plates 12 and 13. Bolts 14 pass through the hubs, and

through these annular plates to hold the several elements in rigid relation. At the outer edges of the disks 10 and 11, a plurality of bolts 15 are arranged, each having its outer end screw-threaded in a disk and its inner end carrying a head which is seated in a recess in the opposite annular plate. Each bolt 15 has a wrench hold near its middle so that it can be tightened to draw the outer 10 edge of the annular plate toward the adjacent edge of the disk.

The buckets carried by the rotor are of unusual construction, and each comprises two tubular portions 17 and 18, converging 15 as shown in Fig. 3, and having their junction point between the annular plates 12 and 13. Each bucket may therefore be described as tubular in shape, and as extending through the rotor from one side to the 20 other. It will be seen that each half of a tubular bucket can be put in place in a rotor disk, before the two halves of the rotor are assembled on the shaft. I prefer to secure each tube to its plates by inserting the tube 25 through holes in the plates and then expanding it by a rolling operation well understood in boiler making. This expansion brings the tube into intimate and tight contact with the plates. After each half of a 30 rotor has been assembled, it can be machined to final size, and then bolted to its companion half, as here shown. The outer faces are then machined to insure true balance. Each bucket can be advantageously 35 cut away at each end, as shown at 19 in Fig. 3, to leave a short tapering vent through which steam may pass, even after the bucket has moved out of direct alignment with the port or channel through which the steam is 40 passing to or from the bucket. This also insures a continuous flow of the steam throughout the whole series, and insuring that all condensation will be blown out at the exhaust pipe. In large sizes, a pipe 9^A (Fig. 45 8) is trapped in the bottom of each steam chest 9, and these are brought together in a main pipe 9^B or header 9^D which connects with a steam trap 9^C.

In the form shown in Figs. 1 and 2, 50 the buckets are grouped in four series: 20, 21, 22, and 23, arranged concentrically, as shown in Fig. 1. Each series may have its own inlet nozzle, and its own outlet, and may have as many expansion chambers or 55 conduits as the particular steam pressure and speed of rotation may seem to justify.

Each nozzle or inlet may be of the type illustrated in Figs. 4 and 5, wherein is shown a feed pipe 24 screw-threaded into a 60 nozzle comprising two parts or halves 25 and 26 seated in the end plate of the engine casing and hollowed out at their adjacent sides to form a discharge port 27 of suitable shape. The ease with which the nozzle can 65 be removed and dismembered for cleaning

or grinding is of importance. The nozzle is preferably set at an oblique angle to the adjacent end of a tubular bucket, and should lie approximately in the plane through which the bucket is moving during the period it receives steam directly from the nozzle. The steam thus received by a bucket is discharged from the opposite end of the bucket.

With a rotor having four sets or series of 70 buckets, I prefer to use four inlet nozzles arranged in pairs, two on either side of the engine, each two being at diametrically opposite points. Thus, if nozzle 24 be arranged to discharge into series 22, then nozzle 28, 80 which supplies the outer row of buckets 20 may be on the same side of the engine as nozzle 24, and located diametrically opposite that nozzle. The other two nozzles 24' and 28' can be arranged in similar manner 85 on the other side of the engine. By thus distributing the points at which the steam enters the rotor, the end thrust of the rotor is equalized, and the strains induced by the driving fluid are adequately distributed. In 90 the form shown, the inlet nozzles are of the expansion or De Laval type. The succeeding nozzles 27^A in each series are tapered so as to converge toward their outer ends, and the nozzles are successively increased in 95 size so as to take care of a certain amount of expansion of the steam which occurs during its passage through a series of buckets, assuming that the inlet nozzles are such as to effect only a partial expansion of the 100 steam.

It will be understood that for each annular series of buckets there may be a series of inlet nozzles, but for the sake of simplicity of the drawings, only one of such 105 inlet nozzles is shown for each series of buckets. The number of buckets through which the steam can be successively passed will of course depend upon the initial pressure of the steam. It will also be noted that 110 when an inlet nozzle registers with a bucket passage, all of the other nozzles of the same series will simultaneously register with bucket passages, thus providing for the free flow of steam throughout the series. The 115 vents 19 insure that each nozzle will deliver steam or fluid to a bucket until the succeeding bucket has come into position for receiving the steam, and there will thus be a continuous flow of steam.

In the modification shown in Figs. 6 and 7, the rotor is the same as that described above, and the end plates 29 and 30 are similar to those of Fig. 2, and carry respectively the annular steam jackets 31 and 32, 120 but the steam chests or conduits mounted within these steam jackets have a different arrangement or grouping from that heretofore described.

Referring to Fig. 6, it will be seen that 125

the steam chests 33, 34 and 35 lead the steam progressively from one series of buckets to a series nearer the axis, and so carry the steam from buckets moving at high velocity 5 toward buckets moving at less velocity, until at the final stage, the steam is discharged through an outlet port 36, arranged in alinement with the innermost train of buckets 33, 34 and 35.

10 In both of the forms shown in the drawings, the rotor is provided in its outer faces with annular grooves 38 and 38^A which tend to reduce leakage in a manner similar to that in which the grooves in pistons tend to 15 reduce leakage.

The operation of either of the modifications illustrated may be described briefly as follows: Steam at high pressure and temperature entering the casing by way of a 20 nozzle, say nozzle 24 of Fig. 3, passes into the adjacent end of a tubular bucket and gives up a portion of its kinetic energy, moving the bucket forward, and thereby turning the rotor and its shaft 1. As the bucket moves 25 forward, the notch or vent 19 at the trailing corner of the bucket allows some steam to enter the bucket until after the succeeding bucket begins to take steam from the nozzle. The nozzle is never entirely shut 30 off by movement of the rotor past its discharge opening.

The steam discharged into the tubular bucket has its direction of movement changed by the angular or curved shape of 35 the bucket, and is also somewhat expanded and cooled within the bucket. It is ultimately forced from the bucket through a port leading to steam chests 9 located within the steam jacket 8. Superheated steam 40 is constantly circulated through this steam jacket, and delivers heat through the wall of the steam chest to the steam within, thereby increasing the temperature and minimizing condensation in the steam chest, and expanding the steam somewhat so that it can 45 be re-delivered to the rotor through a bucket in advance of that wherein the steam was first received. From this second bucket, it can pass through into another steam chest 50 for another re-heating and re-delivery to another bucket, and so on throughout the series to the exhaust chamber. The number of steam chests which can be used with profit in this way depends somewhat on the 55 initial pressure of the steam and on the temperature of the heating medium in the steam jackets, but in general, the aim is to use such a number that when the steam ultimately passes from the engine by way of 60 the outlet port 37 of Fig. 3, the greater part of its available energy will have been taken from it.

In the modification shown in Figs. 1 and 2, the conveyance of steam is from one 65 bucket to another of the same series, but in

the modification shown in Fig. 6, the steam is conveyed each time to a bucket nearer the axis of the rotor, and therefore moving at slower speed, and better suited for contact with steam which has lost part of its 70 initial energy.

The rotor construction herein shown is exceedingly inexpensive as compared with those of the usual turbine rotors, and this construction has the further advantage over 75 usual constructions of admitting of facing the rotor by machining it after it is assembled so as to make it run true, whereas in ordinary constructions in which bucket blades are used, it is necessary to true up 80 the edges of the blades by hand. This feature admits of providing a minimum clearance space between the adjacent faces of the rotor and the surrounding casing.

Although only certain specific embodiments of this invention are herein shown, it will be understood that numerous details of the constructions shown may be altered or omitted without departing from the spirit of this invention, as defined by the following 85 claims.

I claim:—

1. In a rotary engine, a rotor comprising a pair of co-axial disks, and a series of tubes extending between and through said disks to 95 form buckets, said disks having the faces thereof at the ends of said tubes formed to provide elongated ports for the buckets.

2. In a rotary engine, a rotor comprising co-axial disks, and bent bucket tubes of substantially circular transverse shape carried 100 by said disks.

3. In a rotary engine, a rotor comprising co-axial disks, and tubular buckets extending therebetween and arranged in concentric circles. 105

4. In a rotary engine, a rotor comprising plates spaced apart, and buckets carried thereby, each bucket consisting of two straight tubular portions converging toward 110 each other at their place of intersection.

5. In a rotary engine, a rotor comprising a pair of disks, a plate for each disk, a tubular member extending from each disk to the corresponding plate, and means for holding 115 said plates together with the ends of the tubular members in register with each other to form buckets.

6. In a rotary engine, a rotor comprising a pair of disks, a pair of plates between said disks, and tubular members extending between and through each of said plates and the corresponding disk and secured therein by expansion of the ends of said buckets, the meeting ends of said tubular members 120 registering with each other.

7. In a rotary engine, a rotor comprising a pair of disks spaced apart in axial alinement, a pair of plates between said disks, and an annular series of tubular members 125.

extending between each disk and the corresponding plate, said plates being secured together with the tubular members in register with each other, said tubular members meeting at an angle to form bent buckets.

5 8. In a rotary engine, a rotor comprising a pair of disks spaced apart in axial alignment and mounted to rotate on their common axis, and an annular series of bent cylindrical tubular buckets extending between said disks and similarly placed with respect to said axis.

10 9. In a rotary engine, a rotor comprising a plurality of disks, an annular plate for each disk, and tubular buckets passing through said plates and disks.

15 10. In a rotary engine, a rotor comprising a plurality of disks secured together and each having a hub, an annular plate mounted on each hub, and a tubular bucket passing through said disks and annular plates.

20 11. In a rotary engine, a rotor having a plurality of disks, and a tubular bucket passing through said disks and having its ends expanded into tight contact with said disks, the ends of said bucket and the faces of said disks being formed to provide elongated ports.

25 12. In a rotary engine, the combination of a shaft, a pair of disks having hubs secured to said shaft, an annular plate mounted on each hub, means for holding said disks and plates in rigid relation, and a pair of tubes, each having its outer end expanded to form a tight connection with a disk, and each having its inner end expanded to engage an annular plate, said tubes being set at an angle to one another to form a tubular bucket extending through said 30 disks.

13. In a rotary engine, the combination of a casing, a steam chest on either side of said casing, chambers mounted on said casing within said steam chests and heated by steam therein, a rotor within said casing, 45 said rotor having tubular buckets arranged to discharge a driving fluid into one of said chambers and subsequently to receive driving fluid from another of said chambers, and a nozzle for directing the driving fluid into 50 said buckets in succession.

14. In a rotary engine, the combination of a rotor having tubular buckets arranged in concentric circles therethrough, a casing enclosing said rotor, a plurality of nozzles 55 arranged at one side of said casing to project a driving fluid into said buckets, nozzles entering said casing from the opposite side, a plurality of chambers arranged to serve as conduits through which the driving fluid 60 escaping from one bucket may be conducted to another bucket for passage therethrough, and means for reheating the fluid during its passage through said chambers.

15. In a rotary engine, the combination 65 of a casing, a succession of chambers mounted on said casing, means for heating said chambers externally, a rotor within said casing and having buckets, and means for projecting a driving fluid through a bucket into 70 one of said heated chambers, said heated chambers being arranged to conduct said fluid to other buckets in succession.

Signed at Chicago this 26th day of March 1910.

WM. G. ROSS.
